Primary Examiner—Caron D. Veynar
Attorney, Agent, or Firm—John A. Doninger; Taylor J. Ross[57] **CLAIM**

The ornamental design for a seal for cooking vessel, as shown and described.

DESCRIPTION

FIG. 1 is a top, side and end perspective view of a seal for cooking vessel showing my new design;

FIG. 2 is an end elevation view thereof, the opposite end elevation being the same;

FIG. 3 is a side elevation view thereof, the opposite side elevation being the same;

FIG. 4 is a top plan view thereof;

FIG. 5 is a bottom plan view thereof;

FIG. 6 is a top, side and end perspective view of a second embodiment of my new design;

FIG. 7 is an end elevation view thereof, the opposite end elevation being the same;

FIG. 8 is a side elevation view thereof, the opposite side elevation being the same;

FIG. 9 is a top plan view thereof; and,

FIG. 10 is a bottom plan view thereof.
